UNITED STATES PATENT OFFICE.

CLAY W. PREWETT, OF LOS ANGELES, CALIFORNIA, ASSIGNOR TO PREWETT ADDO-
GRAF AND SYSTEM COMPANY, OF LOS ANGELES, CALIFORNIA.

DESIGN FOR A CASING FOR A CALCULATING MACHINE.

Application filed July 23, 1923. Serial No. 6,830. Term of patent 3½ years.

To all whom it may concern:

Be it known that I, CLAY W. PREWETT, a citizen of the United States, residing at Los Angeles, in the county of Los Angeles and State of California, have invented a new, original, and ornamental Design for Casing for a Calculating Machine, for which the following is a specification, reference being had to the accompanying drawing, forming a part thereof.

In the accompanying drawing, Fig. 1 is a perspective view of a casing for a calculating machine, Fig. 2 is a side elevation of the casing and Fig. 3 is a front elevation thereof, showing my new design.

I claim:

The ornamental design for a casing for a calculating machine as shown.
